UNITED STATES PATENT OFFICE.

HEINRICH F. GOETZE, OF BOSTON, MASSACHUSETTS, ASSIGNOR TO ROXBURY CARPET COMPANY, OF SAME PLACE.

DESIGN FOR CARPETS.

Specification forming part of Design No. 8,001, dated January 12, 1875; application filed December 30, 1874.
[Term of Patent 3½ years.]

To all whom it may concern:

Be it known that I, HEINRICH F. GOETZE, of Boston, in the county of Suffolk and State of Massachusetts, have invented a new and original Design for Carpets, of which the following is a specification:

The nature of my design is represented in the accompanying photographic illustration.

What I claim as my invention is—

A design for a carpet, as represented in the accompanying photographic illustration.

In testimony whereof I have signed my name to this specification in the presence of two subscribing witnesses.

HEINRICH F. GOETZE.
